UNITED STATES PATENT OFFICE.

HENRIETTA MEADE WOOTTON, OF BOSTON, MASSACHUSETTS.

ORNAMENTAL ARTICLE.

1,128,929.

Specification of Letters Patent. Patented Feb. 16, 1915.

Application filed March 20, 1914. Serial No. 826,106.

To all whom it may concern:

Be it known that I, HENRIETTA MEADE WOOTTON, of Boston, in the county of Suffolk and State of Massachusetts, have invented a new and useful Ornamental Article, of which the following is a specification.

The main object of my invention is to provide an ornamental work comprising a plurality of elements forming a design and to provide means for suitably holding the elements in their proper relative positions and my invention comprises an ornamental article which accomplishes these objects and in the preferred form I provide a butterfly, a milkweed background and grasses to form a design and these are not only held by other members but also have a coöperating holding function of their own.

In the drawings: Figure 1 is a plan of a plaque embodying my invention; Fig. 2 is an end view thereof; Fig. 3 is a partial section of the device shown in Fig. 1 but on a larger scale; Fig. 4 is a detail of the milkweed fibers being substantially parallel to each other; Fig. 5 is a detail showing the parts of a butterfly; Fig. 6 is a plan showing one ply of waterproof material; and Fig. 7 is a plan showing the double ply of said material.

30 Base A is preferably circular and made of glass and upon it I place the elements of the design these consisting mainly, in the embodiment illustrated, of a fluffy milkweed background B, foliage or grasses D and a butterfly E.

In making the butterfly I prefer to provide a base e of gummed paper upon which is placed the artificial body e', preferably of cardboard or similar material suitably colored. The natural wings e², e² are then stuck on to the base e and the natural feelers e³, e³ are glued to the head portion of the artificial body. This method of making the butterfly results in a relatively flat 45 element of the design which preserves its shape and integrality.

I preferably use the fibers of milkweed as a background because they are white and typify the sky, the butterfly being represented as flying among the grasses or the like such as foliage. The fibers of the milkweed may be parallel as shown in detail in Fig. 4 or the stem may be centrally arranged with relation to its fibers as shown 55 at R' in Fig. 1, this form having the appearance of a star in the sky background.

The yielding fibrous milkweed holds the other elements against lateral displacement, this being clearly illustrated in Fig. 3, it being clear that the milkweed has not only 60 the function of being a part of the design but also the function of holding other elements against lateral displacement which would destroy the design.

The fibers of the milkweed are, of course, 65 in an orderly arrangement and, as illustrated, some of the fibers are in groups with the fibers substantially parallel or side by side and others have the fibers radiating from their stems. Milkweed is lustrous and 70 produces a gleaming or shimmering effect on the eye particularly when in such arrangement, thus imparting a representation or typification of the sky which is enhanced by the winged creature or creatures which 75 are supported by the surface of the milkweed. In other words, the ornamental article as a whole represents the butterfly or other winged creature as in its natural element, viz.: the air, with a brilliant sky as 80 the immediate background for the butterfly.

When the elements are in place a transparent cover F, preferably circular, is brought into position and a strip of flexible moisture proof material G, such as electric 85 tape, is applied so as to cover the edges and extend inwardly along the outer faces of the base and cover. This material is also extended well inwardly between the base and cover so that it not only prevents moisture, 90 air, insects and other foreign matter from entering between the base and cover and holds them together by reason of the adhesion between the glass and the gum of said tape, but it also spaces the base and cover at 95 the proper distance apart so that the elements of the design will be held in proper relative position but will not be crushed and of course some slight pressure may be used because of the yielding nature of the milkweed background. A slight opening may 100 exist at g between the ends of strip G and therefore I provide a similar strip G' of moisture proof material outside of strip G, the ends of strip G' being at g' and therefore the opening g is completely covered by strip G'. These strips G and G' prevent 105 relative rotation between the base and cover and so prevent any possible disarrangement of the design.

Outside strip G is placed a metal rim H which aids in holding the parts together.

I am aware that it has been proposed to mount entomological specimens such as butterflies, by confining them between glass and a cotton batting mat, but cotton possesses no luster, especially when the fibers minutely cross each other as in batting. To obtain the ornamental effect hereinbefore described, it is desirable first that the fibers shall be lustrous, and second that they shall be relatively arranged in an orderly manner with little or no crossing of the uppermost fibers; in other words, that they shall possess an orderly arrangement (not in a disorderly mixture or tangle) so as to obtain the best gleaming appearance to typify the brilliance that appeals to the eye as the concomitant of the butterfly and many other winged creatures.

What I claim is:

- 20 1. An ornamental article comprising a background of milkweed and a winged creature contrasting therewith, the fibers of the milkweed having an artistic arrangement to exhibit their lustrous quality.
- 25 2. An ornamental article comprising a background of milkweed and a winged creature supported by the surface thereof, the

surface fibers of the milkweed exhibiting their lustrous quality, and stems contrasting with the milkweed to indicate foliage or grasses.

3. An ornamental article comprising a background of milkweed and a winged creature supported by the surface thereof, the surface fibers of the milkweed exhibiting their lustrous quality, some of the milkweed having its fibers substantially parallel and some having the fibers radiating from their stems.

4. An ornamental article comprising a background of lustrous fibers and a winged creature contrasting therewith, the fibers having a predetermined variant relationship to exhibit their lustrous qualities in an artistic manner.

5. An ornamental article comprising a background of lustrous fibers arranged to reflect light, and a winged creature contrasting with said fibers.

HENRIETTA MEADE WOOTTON.
